(57) **CLAIM**

The ornamental design for an embossed metal foil, as shown and described.

DESCRIPTION

The sole FIGURE is a top view of an embossed metal foil, the opposite side being a mirror image thereof.

The embossed pattern has a height in the range of 25 mm to 0.001 mm, with the height being the highest in the middle of the "S" figures and the height being the lowest at each end of the "S" figures.

The broken lines in the FIGURE define the bounds of the foil and form no part of the claimed design.
